DESIGN FOR AN ACCORDION

Roberto Pancotti, Nutley, N. J., assignor to Excelsior Accordion Manufacturing Co. Inc., New York, N. Y.

Application May 13, 1936, Serial No. 62,610

Term of patent 7 years

To all whom it may concern:

Be it known that I, Roberto Pancotti, a citizen of the United States, residing at Nutley, county of Essex, and State of New Jersey, have invented a new, original, and ornamental Design for an Accordion, of which the following is a specification, reference being had to the accompanying drawing forming a part thereof.

Fig. 1 is a perspective view of an accordion, showing my new design; and

Fig. 2 is a side elevational view thereof.

I claim:

The ornamental design for an accordion as shown.

ROBERTO PANCOTTI.
